UNITED STATES PATENT OFFICE.

ISAAC HAMMER, OF NEW YORK, N. Y.

DOOR-LOCK.

1,362,417.

Specification of Letters Patent. Patented Dec. 14, 1920.

Application filed October 28, 1919. Serial No. 333,867.

To all whom it may concern:

Be it known that I, ISAAC HAMMER, a citizen of the United States, and a resident of the city of New York, borough of Bronx, 5 county of Bronx, and State of New York, have invented a new and useful Door-Lock, of which the following is a full, clear, and exact description.

The present invention relates in general 10 to door locks and has reference more particularly to a combined permutation and key operated door lock.

The primary object of the invention is to provide a lock which may be operated by 15 either a key or a combination so that in the event that the key is not accessible any one knowing the combination may unlock the lock.

A further object of the invention is to 20 construct the lock of a minimum number of parts and to so arrange the same that the lock may be manufactured at a comparatively modest cost and be easily installed in a small space without materially reconstructing the customary openings which are 25 made in doors and the like to receive the conventional forms of locks and latches.

With these and other objects in view the 30 invention will be more readily understood upon reference to the accompanying drawings and following detailed description the novel points thereof being pointed out in the subjoined claims. In said drawings

Figure 1 is a side elevation of the lock as 35 applied to doors.

Fig. 2 is a cross section on the line 2—2 of Fig. 1.

Fig. 3 is a vertical section through the back of the lock.

Fig. 4 is a vertical section on the line 4—4 of Fig. 1 showing the controlling means active with the parts locked.

Fig. 5 is a section through the line 5—5 of Fig. 4.

Fig. 6 is a view substantially as that of Fig. 4 showing the controlling means inactive the same having been manipulated to inactive position by the combination.

Fig. 7 is a section on the line 7—7 of Fig. 6.

Fig. 8 is a side elevation partly in section showing the manner of moving the controlling means to inactive position by the key.

Fig. 9 is a side elevation of the barrel on 55 which the tumblers are mounted, and its associated parts.

Fig. 10 is a rear view of one of the tumblers.

Fig. 11 is a plane view of the key barrel.

Fig. 12 is a perspective view of the semi-circular disk shaped keys which are used to 60 lock the key barrel on which the tumblers are mounted.

Fig. 13 is a perspective view of a semi-circular disk shaped key which is used for 65 the same purpose as the key referred to in Fig. 12, and

Fig. 14 is a side view of the key for the lock.

Referring to the drawings in detail the 70 lock proposed by the invention is especially adapted for doors to which end, in its preferred form, it is associated with the door A in substantially the same manner as a conventional form of lock in that it is used in 75 combination with an escutcheon plate B and a knob C which is arranged to manipulate the ordinary latch D. In one form of conventional door locks the latch D at all times may be manipulated by the knob C and the 80 door is normally unlocked with the exception of course that the latch D maintains it closed. When it is desired to lock the door, a bolt such as E usually carried beneath the latch D is manipulated to unlocked position 85 by a key which is inserted in the lock through a key-hole in the escutcheon plate. It very often happens that the key is often inaccessible to unlock the door from the outside and considerable inconvenience is 90 experienced when this happens as a person finds that they have been locked out and no chance of obtaining an entrance without the key. According to the present invention it is proposed to provide as heretofore stated, 95 a combined permutation and key operated lock to which end provision is made whereby the bolt E may be either locked or unlocked by the combination or by the key. Thus it will be seen should the key to the 100 lock be lost the door may be either locked or unlocked by a combination. With this end in view and according to the preferred construction of the invention the key barrel 1 (see Fig. 11) comprises a tubular member 105 with the key slot 2 made therein to receive the key 3. The inner end of this barrel is reduced in thickness to provide a rectangular extension 4 which is made to engage the end F of the bolt E so that rotation of the 110 barrel 1 by the key 3 will slide the bolt E to and from locked and unlocked position,

The bolt E is mounted in the housing G with the guides H arranged to insure proper sliding movement of the bolt through the opening 1 in the face of the housing G. The key 5 barrel 1 is co-axially received in the tumbler barrel 5 and in which it is free to rotate when manipulated by the key 3 or by the combination arrangement which will be presently described. This tumbler barrel 5 10 is fixed against either longitudinal or rotary movement by the flange collar 6 which is mounted on the barrel intermediate its ends. Positioned adjacent the flange 6 is a vertical split post 7 between the confronting faces of 15 which is pivoted the dogging or controlling device 8 one end of which terminating in a downwardly presented finger 9 extends through a slot or opening 10 in the top of the tumbler barrel 5 in front of the post 7 20 the extreme end of the finger being received in a slot or opening 11 in the end of the key slot 2 in the key barrel 1. So long as the finger 9 of the controlling or dogging device 8 is presented through the opening 10 and 25 into the slot 11 the key barrel 1 will be held against rotary movement in the tumbler barrel 5, thus it will be seen to unlock the lock, the finger 9 of the dogging or controlling device 8 must be disengaged from the slot 11. 30 It therefore follows that this dogging or controlling device is a common control for both the permutation and the key and must be manipulated in each case by separate means. When the key 3 is inserted in the 35 slot 2 of the barrel 1 (see Fig. 8) the end of the key on being inserted will raise the finger 9 out of the slot 11 permitting the key barrel to be turned to manipulate the bolt E. A spring 13 with one end fixed as at 40 14 on the face of the flange 6 is provided to induce a lifting effect on the under side of the end of the dogging device opposite the finger 9, which will normally maintain the finger in locking engagement with the barrels 1 45 and 5. The strength of this spring is such as to enable it to be overcome in raising the dogging device by the key. To maintain the key barrel 1 in the tumbler barrel 5 and to permit rotation of the key barrel, and at the 50 same time preventing a longitudinal movement of the key barrel the tumbler barrel is provided with a pair of slots 15 on its top which extend about 90° about its circumference and with a single slot as at 16 which 55 is substantially the same as the slots 15 with the exception that it is on the bottom of the barrel and located nearer the end of the barrel. The key barrel 1 is provided with a like number of grooves 17 which extend 60 continuously around the barrel and made to register with the slots 15 and 16 in the tumbler barrel. Received by the slots 15 are a pair of semi-circular disk shaped keys 18 which are seated in the slots 15 with their 65 ends terminating in two of the grooves 17

of the key barrel. Both of these keys 18 are provided with radial slots 19 which are of a size to leave an unobstructed opening for the key through the key slot 2. The single key 20 which is received by the slot 16 terminates with its end received in the third groove in the key barrel. As this key is presented on the under side of the barrel it need have no slot to accommodate the key. These keys are confined in the slots 15 and 70 16 so as not to leave them protruding above the circumference of the barrel 5. 75

As so far described it will be readily seen wherein a key such as 3 inserted in the key slot 2 of the barrel 1 will raise the finger 9 80 of the dogging device 8 and release the key barrel 1 so that it may be rotated relative to the tumbler barrel 5 and with the rectangular end 4 manipulating the bolt E. Just as soon as the key 3 is withdrawn the 85 influence of the spring 13 will present the finger 9 in locking position relative to the two barrels and further manipulation of the bolt E will be prevented.

In the absence of the key the combination 90 must be manipulated to actuate the dogging device and leave the key barrel 1 free to be rotated. In the first place the key barrel is provided with a manipulating knob 21 which is presented on the extreme end of the 95 barrel and fixed thereto in any suitable manner such as by the pin 22. With this knob the barrel may be rotated when properly released. As stated the flange 6 is mounted intermediate the ends of the tumbler barrel 100 5. This flange is provided with a concentric collar or annular abutment 23. The tumblers for the combination according to the showing made are three in number, namely 105 24, 25 and 26 all of which being coaxially mounted with freedom of rotation on the tumbler barrel 5, the first of which, namely 24 is adapted to bear against the annular collar 23. All these tumblers are provided with annular slots 27, 28 and 29 all of which 110 being of the same size so that when brought into registering relation to each other they offer a relatively long slot. The tumbler barrel is provided with diametrically opposed longitudinal grooves 30 made to receive the tongues 31 of the rings 32 which are positioned between the confronting faces of the tumblers. An annular face plate 33 is provided on the outside of the lock the same having radial bolts 34 extending from 115 its inner face longitudinally on both sides of the tumbler barrel 5 with its ends extending through the ears 35 on opposite sides of the flange 6 and terminating through openings made to receive them in the housing G. Suitable nuts 36 being threaded on the bolts so that they may be screwed up to bear against the ears 35 to draw the face plate 33 toward the flange 6 and confine the tumblers against longitudinal movement on 120 125 130

the barrel 5. Suitable nuts 37 are also provided for mounting the housing G to the door A by these bolts. Co-axially mounted on the inside of the face flange 33 is a manipulating disk 38 for the tumblers. This disk is provided with a manipulating knob 39 centered on the outside of the face plate 33. The disk 38 has an axial opening through which the barrel 5 extends and a cam slot 40 in its circumference, the purpose of which will be presently described. Located on the inner face of this disk 38 is a lug 41, the purpose of which will also be described presently. Each of the tumblers 5 with the exception of the one represented as 24, which is a plain face bearing against the collar 23, are constructed with lugs 41 on one face and grooves 42 on their opposite face. These grooves are produced in a manner to leave annular flanges 43 on which are mounted with a limited rotatable movement ring members 44. These grooves 42 are constructed with relatively short slots 45 made to receive abutments 46 on the annular ring members 44. While the grooves 42 and the annular rings 44 with their abutments 46 are constructed alike in each of the tumblers, the slots 48 while of substantially the same size are of course positioned at diametrically opposite points in the grooves 42 the purpose of which will be obvious upon a further reading of the description. As stated, each of the tumblers with the exception of the one recited as 24 is provided with lugs 41. 35 As the tumblers are arranged with their respective grooves presented in the same direction the lugs 41 are presented in the grooves of adjacent tumblers, that is a lug 41 on one tumbler is presented in the groove 42 of an adjacent tumbler. With this construction while the tumblers each to the other are capable of rotation the extent of this rotation is limited by the lugs 41 and the abutments 46. As previously stated the 40 manipulating disk 38 is also provided with a lug 41 which is presented in the groove 42 of an adjacent tumbler. It therefore follows that by manipulating the knob 39 and thus rotating the manipulating disk 38 the lug 41 on the disk 38 will sooner or later contact with the abutment 46 in the groove of the adjacent tumbler and when this contact is made a further rotation of the disk 38 will bring its corresponding lug in contact with the abutment of the groove of the next tumbler. By a still further rotation of the knob 39 in the same direction, the lug 41 on the intermediate tumbler namely 25 will be brought into contact with the abutment 46 in the groove of the last tumbler, namely 24, whereupon all of the tumblers are rotated in unison by the knob 39. Say for instance, the knob 39 in accomplishing the result just mentioned has been rotated 60 to the right. Just as soon as the pointer 47

has been presented opposite the proper graduation on the face plate 33 it will be known that the tumbler 24 has been rotated to present its slot 27 in the desired position. The manipulating knob 39 is then reversed 70 or rotated in a reverse direction whereupon the tumbler 24 will have been released. As the lug 41 on the adjacent tumbler will travel in the groove 42 of the tumbler 24 in a direction away from the abutment 46, at 75 the same time the lock on the tumbler 24 will contact with the abutment 46 in the tumbler 25 and bring this tumbler to the desired position with its slot 28 coinciding with the slot 27 in the tumbler 24. The 80 knob 39 is now turned to the right whereupon the lug 41 on the manipulating disk 38 will bring the slot 29 in the tumbler 26 in register with the slots 27 and 28. The knob 39 will then again be rotated in a direction opposite to this last rotation until the cam slot 40 therein registers with the slots, 27, 28 and 29. With the tumblers in this position the arrangement is such as to permit the weighted yoke 47 which is pivotally mounted on the spindle 48 which in turn is journaled as at 49 and 50 to drop into the slots 27, 28, 29 and 40 and in so doing it will have a wiping connection with the end 51 of the dogging device 8 which is 90 presented in the path of the weighted yoke whereupon by the influence of the spring 52, which is stronger than the spring 13, the weighted yoke will rock the dogging device about its pivot and thus disengage the finger 100 9 from the slot 11 in the key barrel 1, permitting the knob 21 to be manipulated to rotate the key barrel 1, and slide the bolt E. The tendency of the spring 52 is of course to press downwardly on the weighted yoke 105 47. However so long as the slots in the tumblers are not registered to present a relatively long opening the yoke will ride over the tumblers, but just as soon as the combination has been arranged to register the slots 110 in the tumblers the yoke will fall in to them and in so doing will raise the dogging device as previously described. Of course the combination as set forth may be varied as occasion demands and the number of tumblers be more or less according to the arrangement of the combination. 115

Having thus described my invention, what I claim as new and desire to secure by Letters Patent is as follows:—

1. In a lock, and in combination, a tumbler barrel, a key barrel rotatably mounted in the tumbler barrel, and adapted to actuate the bolt of a lock, means for controlling the rotation of the key barrel and separate 125 means for independently actuating said controlling means, comprising respectively a key received by the key barrel and a permutation mechanism co-acting with the tumbler barrel.

2. In a lock, and in combination, a tumbler barrel, rotatable tumblers on said barrel, a key barrel rotatably mounted in the tumbler barrel, and adapted to actuate the bolt of a lock, means for controlling the rotation of the key barrel and means for actuating said controlling means, comprising a key received by the key barrel, in one instance and the manipulation of the tumblers on the tumbler barrel in another instance.
3. In a lock, and in combination a tumbler barrel, a key barrel rotatably mounted in the tumbler barrel and adapted to actuate the bolt of a lock, means for controlling the rotation of the key barrel, and dual means for actuating said controlling means.
4. In a lock, and in combination, a tumbler barrel, rotatable tumblers on said barrel, a key barrel rotatably mounted in the tumbler barrel, and adapted to actuate the bolt of a lock, means for controlling the rotation of the key barrel and dual means for actuating said controlling means, comprising a key received by the key barrel, in one instance and the manipulation of the tumblers on the tumbler barrel in another instance.
5. In a combined permutation and key operated lock, a tumbler barrel, rotatable tumblers on said barrel, a key barrel rotatably mounted in the tumbler barrel hav-
- ing an operative connection with the bolt of the lock, a controlling device connecting with the tumbler barrel and the key barrel to prevent rotation of the latter in the former, means coöperating with the rotatable tumblers adapted to move the controlling means to inactive position, when the tumblers have been manipulated in accordance with a combination, said controlling means being also movable to inactive position by the insertion of a key in the key barrel.
6. In a lock and in combination, a tumbler barrel having an opening therethrough, rotatable tumblers on said barrel, a key barrel having a slot therein, rotatably mounted in the tumbler barrel and adapted to engage with the lock for actuating the bolt thereof, an actuating mechanism for the tumblers, and means for controlling the rotation of the key barrel, comprising a dogging device pivoted on the tumbler barrel and tumbler controlled means for releasing the same, one end of said dogging device extending through the opening in the tumbler barrel and into the key slot, the opposite end of said dogging device extending adjacent the tumblers and in the path of movement of the tumbler controlled releasing means.

ISAAC HAMMER.
